UNITED STATES PATENT OFFICE.

ACHILLES ALLEN, OF MILTON, OREGON, ASSIGNOR OF ONE-THIRD TO THOMAS CROWLEY FRAZIER AND ONE-THIRD TO ORA ESTES SMITH, BOTH OF MILTON, OREGON.

AMALGAMATOR.

1,172,099.

Specification of Letters Patent. Patented Feb. 15, 1916.

Application filed February 25, 1915. Serial No. 10,497.

To all whom it may concern:

Be it known that I, ACHILLES ALLEN, a citizen of the United States, residing at Milton, in the county of Umatilla and State of Oregon, have invented certain new and useful Improvements in Amalgamators; and I do declare the following to be a full, clear, and exact description of the invention, such as will enable others skilled in the art to 10 which it appertains to make and use the same.

This invention relates to improvements in amalgamators especially designed for quartz mills.

15 The main object of the invention is to construct a machine of this character in which every particle of the precious metal will be saved and in which there is no waste of the mercury used.

20 Another object of the invention is to provide an amalgamator which is simply constructed and which may be operated without any attention or expense whatever when finely ground pulp is fed to it.

25 With these and other objects in view, the invention consists of certain novel features of construction, and the combination and arrangement of parts as will be more fully described and claimed.

30 In the accompanying drawings: Figure 1 represents a side view of an amalgamator constructed in accordance with this invention; Fig. 2 is a longitudinal vertical section thereof; Fig. 3 is a horizontal section 35 taken on the line 3—3 of Fig. 2, with the funnel removed; Fig. 4 is a similar view taken on the line 4—4 of Fig. 2. Fig. 5 is a similar view taken on the line 5—5 of Fig. 2.

40 In the embodiment illustrated, a trough 1 for receiving and conducting off the pulp after it has been treated is shown in the form of an annulus mounted on suitable legs 2 and having an outlet 3 here shown in 45 the form of a spout. This trough 1 is slightly inclined to cause the refuse water and pulp to run out through the spout into sluice boxes not shown.

Disposed centrally of the trough 1 is a 50 mercury vat 4 here shown in the form of a cylinder constructed of steel and having

an amalginating plate 5 extending laterally from its upper edge and inclined upwardly and outwardly toward the rim thereof. This plate is shown as circular in formation and 55 is provided near its edge with an annular groove 6 in its upper face for a purpose to be described, and at its edge is provided with a downturned rim 7 for directing the pulp which flows over said edge into the 60 trough 1 below it, said plate being slightly greater in diameter than the inner diameter of the trough to position it in vertical alignment with said trough. This plate 5 may be of any desired size being preferably about 65 four feet in diameter and the periphery of which is supported by suitable braces hereinafter described. This plate 5 is preferably constructed of copper silver plated, the plating operating to prevent verdigris from 70 rising from the copper and fouling the mercury which comes in contact with the plate as will be hereinafter described. A discharge cock 8 is disposed at the bottom of vat 4 for drawing off the mercury and amalgam when desired.

A metal cylinder 9 is shown preferably constructed of sheet steel which is open at both ends and is provided at its lower end with a plurality of legs 10 extending in 80 longitudinal alignment with the cylinder walls and which are designed to rest on the bottom of the vat 4 and space the lower edge of said cylinder the desired distance from said vat bottom. Disposed around the 85 outer face of this cylinder 9 near its lower end are a plurality of spacing elements 11 of uniform size which are designed to engage the inner face of the vat 4 and thus space said cylinder 9 the desired distance 90 from the walls of the vat and afford ample space between said cylinder and vat for the upward passage of the pulp therebetween as will be hereinafter described. This cylinder 9 is also provided on its outer face at 95 a suitable point intermediately of its ends with laterally extending peripherally aligned lugs 12 which are designed as locks for holding a second collar or plate 13 in operative position relatively to the plate 5 as 100 will be hereinafter further described.

Suitable brace rods 14 are connected at

one end to the outer face of the cylinder 9 at spaced intervals around its periphery preferably near the upper end thereof and extend obliquely therefrom being provided at their lower or free ends with clips 15 which are designed to engage the lower edge of the rim 7 of the plate 5 and thus afford ample support for said plate, said clips being here shown adjustably mounted on these rods by means of nuts 16 between which and other lock nuts or stops 17 the clips are mounted and by tightening the nuts 16 said clips may be caused to firmly engage the rim of the plate 5.

16 A pulp receiving cylinder or funnel 18 is shown mounted in the cylinder 9 having its flared mouth projecting above the upper end of the cylinder and provided at the base of said mouth with an annular shoulder 19 which is designed to rest on the upper edge of the cylinder 9 and support said funnel in operative position relatively to said cylinder. The smaller discharge end of the funnel 18 is disposed slightly above the lower end of the cylinder 9 and said funnel is braced within the cylinder 9 by means of radially extending brace bars 20 which engage the inner walls of the cylinder 9 and brace said funnel and space it from said side walls.

Disposed within the bottom of the mercury vat 4 are a plurality of superposed perforated annular plates 21, any desired number of which may be employed, four being here shown with the lowermost made wider than the others and being substantially of the same size as the lower end of the cylinder 9, the other plates of the series being smaller and being connected by bolts 22 passing through them and on which between said plates are mounted spacing plates or washers 23. These plates 21 are preferably constructed of copper silver plated, and operate to save the amalgam which gathers between them. These plates being connected by bolts may be separated when the clean-up is made and the amalgam removed from between them.

The plate 13 which is designed to co-operate with the plate 5 is made in the form of an annulus with a collar 24 extending at right angles from its inner edge and which is designed to rest at its lower edge on the upper face of the plate 5 and space said plate 13 a distance equal to the width of the collar above said plate 5 at the central inner portions thereof where they surround the cylinder 9. This plate 13 is inclined downwardly and outwardly and is provided at its peripheral edge with an upturned flange or rim 25 to provide a discharge mouth 26 between said plates which is arranged at the inner edge of the groove 6 in the plate 5, said plate 13 being of a diameter substantially equal to the diameter of the plate 5

taken from the inner edge of its groove. When the parts are assembled this plate 13 encircles the cylinder 9 below the lugs 12 on said cylinder which are designed to rest on the upper edge of said plate 13 and in connection with clips 15 hold the plate down in operative position and prevent it from moving upwardly under the action of the flowing pulp.

The collar 24 is provided with a plurality of apertures 27 spaced apart, and projecting from its inner face at diametrically opposite points are laterally extending studs 28 which are designed to form stops for limiting the turning motion of a flat ring 29 which is disposed within the collar 24 and is provided with a plurality of apertures 30 which are designed when said ring is turned in one direction to register with the apertures 27 in the collar 24 and when it is turned in the opposite direction these apertures are placed out of register so that there is no outlet then formed between the plates 5 and 13, it being obvious that these registering apertures 27 and 30 are designed as outlets to permit the pulp rising between the cylinder 9 and said collar to flow out between the plates as will be presently described.

The flat ring or collar 29 is provided in its upper edge at diametrically opposite points with recesses 31 into which the studs 28 of the collar 24 are designed to extend and the opposite ends of these recesses coact with said studs for limiting the movement of said ring in opposite directions. An operating handle 32 for the ring 29 is here shown in the form of a rod projecting upwardly from said ring and which is designed to be grasped and operated for turning the ring relatively to the collar 24. From the above description it will be obvious that this ring 29 operates as a valve for opening and closing the discharge openings in the collar 24.

In the operation of this apparatus the bottom of the vat 4 is covered with a quantity of mercury sufficient to inclose the discharge end of the cylinder 9. The pulp or slime is then fed into the mouth of the funnel 18 which is of sufficient height to give the feeding mass ample pressure to force its way through the mercury in the vat 4 and while so doing a portion of the mercury will separate into minute particles and mingle with the slime or pulp as it boils up between the walls of the cylinder 9 and the vat 4. By this boiling action the whole mass is kept in constant agitation thereby causing the particles of precious metal contained in the pulp to come in contact with the mercury forming an amalgam. As the agitated mass is finally forced upward between the cylinder 9 and the collar 24 of the plate 13, said ring 29 having been first

turned to bring the openings therein into register with the openings in said collar, the boiling pulp will pass through said openings and up over the outer face of the plate 13, the passage of the pulp through the openings serving to retard its progress and thereby more thoroughly agitate it and cause it to be evenly distributed over the face of the plate 5. The passage of the pulp 10 up over the inner edge of the plate 13 also produces an additional agitation and causes the pulp to be evenly distributed over the downwardly inclined face of the plate 13. The pulp then flows over the faces of the 15 plates 5 and 13, passes over the upturned flange of the plate 13, into the trough formed by the groove 6 of the plate 5, and any particles of mercury or amalgam which remain in the pulp are caught in said groove 20 and returned through the pipe or tube 8 to the vat 4. The mass upon passing over the rim of the plate 5 drops into the trough 1 and passes out through the spout thereof into the sluices not shown.

25 From the above description it will be obvious that the parts may be quickly assembled or disassembled and while simple in construction present a maximum surface for collecting the amalgam contained in the out- 30 flowing pulp.

I claim as my invention:

1. An amalgamator comprising a mercury vat, a cylinder mounted therein and spaced from the side walls and bottom thereof, a pair of vertically spaced laterally extending plates mounted on the wall of said vat and converging toward their outer edges, a wall between said plates having pulp supplying openings therein, the lower 35 plate being wider than the upper, with its free edge extending beyond the edge of the upper plate and provided with a trough to receive the pulp discharged from said upper plate.

45 2. An amalgamator comprising a mercury vat, a cylinder mounted therein and spaced from the side walls and bottom thereof, a feed supply funnel extending into said cylinder, a pair of vertically spaced laterally 50 extending plates mounted on said vat and converging toward their outer edges, the lower plate being wider than the upper, and valved supply means arranged between said plates.

55 3. An amalgamator comprising a mercury vat, a cylinder mounted therein and spaced from the side walls and bottom thereof, a feed supply funnel extending into said cylinder, a pair of vertically spaced laterally 60 extending plates mounted on said vat and converging toward their outer edges, the lower plate being wider than the upper and projecting at its outer edge beyond the outer edge of the upper plate and provided with a groove in its upper face beyond the outer

edge of the upper plate, and means under the control of the operator for supplying pulp between said plates.

4. An amalgamator comprising a mercury vat, a cylinder mounted therein and spaced 70 from the side walls and bottom thereof, a feed supply funnel extending into said cylinder, a pair of vertically spaced laterally extending plates mounted on said vat and converging toward their outer edges, the 75 lower plate being wider than the upper and projecting at its outer edge beyond the outer edge of the upper plate and provided with a groove in its upper face beyond the outer edge of the upper plate, means under the 80 control of the operator for supplying pulp between said plates, and a pipe leading from said groove to said vat.

5. An amalgamator comprising a mercury vat, a cylinder mounted therein and spaced 85 from the side walls and bottom thereof, a feed supply funnel extending into said cylinder, a pair of vertically spaced laterally extending plates mounted on said vat and converging toward their outer edges, a collar 90 carried by one of said plates and arranged between them to form a closure at their inner edges, said collar having apertures therein, and an annular plate slidably mounted on said collar and having apertures there- 95 in positioned to register at predetermined intervals with the apertures in said collar.

6. An amalgamator comprising a mercury vat, a cylinder mounted therein and spaced from the side walls and bottom thereof, a 100 feed supply funnel extending into said cylinder, a pair of vertically spaced laterally extending plates mounted on said vat and converging toward their outer edges, a collar carried by one of said plates and arranged 105 between them to form a closure at their inner edges, said collar having apertures therein, an annular plate slidably mounted on said collar and having apertures therein positioned to register at predetermined in- 110 tervals with the apertures in said collar, and coöperating means on said collar and plate for limiting the turning movement of the latter in opposite directions.

7. An amalgamator comprising a mercury 115 vat, a cylinder mounted therein and spaced from the side walls and bottom thereof, a plurality of vertically spaced perforated ring like plates disposed in said mercury vat, the lowermost plate of said series being 120 wider than the other, spacing washers disposed between said plates, and bolts adapted to pass through said plates through the spacing washers to connect the same and a funnel member on the cylinder adapted to 125 deliver material within said series.

8. An amalgamator comprising a mercury vat, a cylinder mounted therein and spaced from the side walls and bottom thereof, a feed supply funnel extending into said cyl- 130

inder, a pair of vertically spaced laterally extending plates mounted on said vat and converging toward their outer edges, the lower plate being wider than the upper, 5 valved supply means arranged between the plates, and brace rods secured to said cylinder and engaged with said lower plate.

In testimony whereof I have hereunto set my hand in presence of two subscribing witnesses.

ACHILLES ALLEN.
